UNITED STATES PATENT OFFICE.

HARRY A. LEWIS, OF NORRISTOWN, PENNSYLVANIA, ASSIGNOR TO WESTINGHOUSE ELECTRIC AND MANUFACTURING COMPANY, A CORPORATION OF PENNSYLVANIA.

ELECTROMAGNET APPARATUS.

1,339,900.

Specification of Letters Patent. Patented May 11, 1920.

Application filed May 22, 1911. Serial No. 628,733.

To all whom it may concern:

Be it known that I, HARRY A. LEWIS, a citizen of the United States, and a resident of Norristown, in the county of Montgomery and State of Pennsylvania, have invented 5 a new and useful Improvement in Electromagnet Apparatus, of which the following is a specification.

My invention relates to electro-magnets 10 and electromagnetically actuated switches for the control of electric circuits.

One object of my invention is to provide an electro-magnet comprising a single coil or a plurality of coöperating coils and a 15 movable armature or core that is actuated only by the energization of said coil or coils within predetermined limits. A second object of my invention is to provide an electric switching device that is actuated by 20 an electro-magnet having the characteristics above referred to. For convenience, a switch of this character will hereinafter be referred to as a magnet switch.

Control systems of the unit-switch type 25 have been largely used for governing electric motors and have comprised a plurality of independently operated switches designed and connected to act successively to produce a gradual and automatic acceleration of the 30 motors with which they have been associated. In these systems, some independent means is ordinarily employed for delaying the action of the successive switches in order to avoid injuring the motor by excessive current.

While my present invention, broadly considered, consists of an electromagnetic device having peculiar operating characteristics, in a more limited aspect, it consists 40 of a magnet switch that is particularly adapted for use in unit-switch control systems.

The magnet switch of my invention has the characteristic of occupying its open position, not only when its actuating magnet is deenergized, but also when it is energized above a predetermined value. In other words, the switch is closed only when energized between predetermined limits. By 50 utilizing a plurality of switches of this character in a simple unit-switch control system, the acceleration of an electric motor may be advantageously accomplished and the action of each switch delayed until

the current traversing the motor circuit has 55 sufficiently decreased to fall within the limits which determine the action of the switches.

In addition to the above-named characteristics, the switch, when closed, will remain 60 closed until its actuating magnet winding is deenergized, unless the current traversing the coil becomes excessive.

Figure 1 of the accompanying drawings 65 is a partially sectional elevation of a magnet switch having the operating characteristics of my invention and arranged and constructed in accordance therewith. Fig. 2 is a similar view of a modified structure also embodying my invention. Figs. 3 and 4 70 are diagrams illustrating the application of the switches shown respectively in Figs. 1 and 2 to simple systems of electric motor control. Fig. 5 is an elevation and Fig. 6 is a plan view, partially in section, of a 75 magnet switch that is similar to the switch of Fig. 2, except that four, instead of two, independently movable core members or armatures are provided.

Referring to Fig. 1 of the drawings, the 80 switch here shown comprises a stationary magnetizable member 1, movable magnetizable members 2 and 3, stationary switch contact members 4 and 5, movable switch contact members 6 and 7 and actuating coils 85 8 and 9.

The stationary member 1 is rectangular in 90 form and comprises a central branch 10 of relatively large cross section on which the coils 8 and 9 are both mounted, and side 95 branches 11 and 12, which are connected, through the branches 28^a and 29^b, to the ends of the branch 10 outside of the coils 8 and 9 and are inset at 13 and 14 between the coils so that they come into contact, or substantially into contact, with the central branch 10 at these points. The portions of the side branches 11 and 12 which extend to the inset portions 13 and 14 are, for convenience, labeled 29^a and 28^b.

The movable members 2 and 3 are alike and comprise arms 15 and 16 that are pivotally secured to the stationary member 1 at 17 and 18 and are disposed substantially parallel to the side branches 11 and 12. The 105 said arms are severally provided with lateral projections 19 and 20 that extend into recesses 21 and 22 formed by the inset por-

tions 13 and 14 of the side branches 11 and 12 of the stationary member 1; inwardly projecting arms 23 and 24 and contact-bearing arms 25^a and 26^a, to which the members 6 and 7 are attached. The widths of the air gaps between the ends of the projections 19 and 20 and the inset portions 13 and 14 are determined by adjusting screws 27^a and 27^b with which the lower ends of the arms 15 and 16 are provided.

The coils 8 and 9 are connected to act in conjunction with each other electrically as a single coil or they may have different structural and functional characteristics; for example, the coils may be parts of a single series winding, or the coil 8 may be a high resistance shunt coil supplied with small current, while the coil 9 may be a low-resistance series coil.

The magnetic flux established by the coil 8 traverses the circuits comprising the central branch 10, the side branches 11 and 12 and the branches 28^a and the portions 29^a. That portion of the stationary magnetizable member 1 which is included in the circuits becomes energized to attract the armatures 23 and 24; and being of magnetizable material, it will tend to maintain the flux within its own confines. If the flux, however, is above a predetermined value, sufficiently large to saturate the above-traced circuits, it will traverse additional circuits comprising the central branch 10, the inset portions 13 and 14, the recesses 21 and 22, the side branches 11 and 12 and the branches 28^a. The flux will leak beyond the confines of the circuits just traced to enter the projections 19 and 20, the arms 15 and 16 and the armatures 23 and 24. This leakage flux will aid the magnetism of the saturated circuits to close the switch members. The flux will even traverse the full length of the central branch 10, continuing by way of the branches 29^b and the lower portions of the branches 11 and 12, across the recesses 21 and 22. This path is rendered particularly easy of travel because the flux of the coil 9 is in the same direction as that of the coil 8. The excess or leakage flux traversing the recesses 21 and 22 will, of course, act upon the projections 19 and 20 with forces opposing the forces acting upon the armatures 23 and 24.

The magnetic flux set into operation by the shunt coil 8 is thus adapted to actuate the switch members 7 and 6, through its influence upon the armatures 23 and 24, and to oppose such actuation, through its influence upon the projections 19 and 20. This is a very important feature; for variations in line voltage or in the temperature of the shunt coil 8 result in varying both the forces acting upon the armatures 23 and 24 and the projections 19 and 20, so that the time of closing of the switch members 7 and 6 is

almost wholly independent of such variations, being dependent upon the decrease in the flux of the series coil 9 alone.

The operation of the electro-magnet and of the switch contact members actuated by it is as follows:

Assuming that the coils 8 and 9 are independently connected and only the coil 8 is energized, the arrangement of parts is such that the arms 23 and 24 will be attracted to the adjacent end of the branch 10 and the switch contacts 6 and 7 will be moved into engagement with the stationary members 4 and 5. If, however, the coil 9 is strongly energized while energy is supplied to the coil 8, a leakage magnetic flux will traverse the air gaps provided by the screws 27^a and 27^b and either the arms 15 and 16 and the central branch 10 or portions of the arms 15 and 16 and the projections 19 and 20 that will be of sufficient strength to overbalance the pull upon the arms 23 and 24 and prevent the closing of the switch contact terminals until the current in the coil 9 falls below a predetermined value. When the said current reaches such predetermined value, one of the movable members 2 and 3 will be actuated by the magnetic pull exerted upon the arms 23 and 24 and the corresponding switch will be closed. It is evident that, if only a single pair of switch contacts is desired, only one of the movable members 2 and 3 is necessary. Theoretically, both of the movable members can be made to act at the same time by adjusting the air gaps with sufficient care, but, practically, it is impossible to maintain such an action under ordinary operating conditions and, consequently, I prefer to use a single movable member for one set of switch contacts and, if two or more members are employed, to so adjust the air gaps that they will act successively to close two independent switches instead of acting together.

In the modified structure shown in Fig. 2, which operates on the same principle as the structure shown in Fig. 1, only a single coil 25 is employed. The switch comprises, in addition to the coil 25, a central core member 26 on which the coil is mounted, a U-shaped member 27, transverse members 28 and 29 located at the respective ends of the member 27 and movable core members 30 and 31.

Movable switch contact members 32 and 33 are respectively attached to the upper ends of the members 30 and 31 to coöperate with stationary contact members 34 and 35. The movable core members or armatures 30 and 31 are pivotally attached to the respective ends of the member 29 at 36 and 37, the switch contact members being separated, when the coil 25 is deenergized, by springs 38 and 39 which hold the armatures 30 and 31 close to the adjacent ends of the member 130

28. The armatures are prevented from coming into engagement with the member 28 by means of screws 40 and 41 that may be adjusted to vary the air gaps between the said parts. The cross sectional area of the transverse member 29 is materially less than the corresponding area of the U-shaped member 27 and the extremities of the members 30 and 31 are relatively close and parallel to the member 29 so that, when the coil 25 is energized, there is always a flux tending to oscillate the armatures about their pivotal points and to close the switches.

If the coil 25 is energized above a predetermined value, there is a material leakage flux through the member 28 across the air gaps 42 and 43 and back to the lower end of the central core member 26, through the member 29 and the lower ends of the armatures 30 and 31. This flux obviously tends to hold the switch open, since the air gaps 42 and 43 are materially farther from the pivotal points 36 and 37 than the point of application of the forces which tend to close the switch. If the coil 25 is connected in series with a motor supply circuit and the switch contact terminals are arranged to exclude motor starting resistance, it is evidently possible to so design the coil 25 and its core members that the first rush of current, when the motor circuit switch is closed, will prevent the immediate closing of the switch contacts and, as the motor accelerates and the current dies down, the armature 30, having the larger air gaps at 42, will be actuated and the contact terminals 32 and 34 be brought into engagement with each other. It is also evident that another rush of current will then result which will tend to still further delay the closing of the switch contact terminals 33 and 35.

The operation of the switches shown in Figs. 1 and 2 will be considered more in detail in connection with the diagrams of Figs. 3 and 4 to which reference will now be had.

In Fig. 3 energy is supplied to motor 44 from any suitable source of electricity through line conductors 45 and 46, the direction of motor rotation being controlled by reversing switches 47, 48, 49 and 50, and the acceleration of the motor being controlled by resistor sections 51, 52, 53 and 54 and magnet switches 55 and 56 which severally correspond to the switch of Fig. 1. Assuming that the switches occupy the positions shown in the drawing, if master switch 57 is moved into position *b*, energy is supplied from conductor 46, through conductor 58, switch 57, conductor 59, coils 60 and 61 of switches 47 and 50, conductor 62, switch 57 and conductor 63 to the opposite line conductor 45. The reversing switches 47 and 50 are immediately closed and the motor circuit is established from line con-

ductor 46 through one side of a knife blade switch 64, conductor 65, switch 47, conductor 66, motor armature 67, conductor 68, switch 50, series coil 69 of relay switch 70, conductor 71, resistor sections 51 to 54, inclusive, series coils 72 and 73 of electro-magnets 56 and 55, conductor 74, motor field magnet winding 75, conductor 76, overload release circuit breaker 77, one blade of switch 64 and conductor 78 to opposite line conductor 45. The magnet switches 55 and 56 are respectively provided with shunt coils 79 and 80 which are supplied with energy from conductor 46, through conductor 65, relay switch 81 (which is closed when switch 49 is open) and relay switch 70, circuit being completed from opposite terminal of coil 79 to the middle point of the accelerating resistance and from the opposite terminal of coil 80 to one terminal of the resistance.

As already explained in connection with Fig. 1, the energy supplied to the coils 79 and 80 tends to actuate the armatures of the switches 55 and 56, but the action of the series coils 72 and 73, although they are connected electrically in the same direction as coils 80 and 79, tends to prevent movement of the armatures until the motor current falls below a predetermined value. The action of the magnet switches may be properly adjusted by varying the number of turns in the windings 72, 73, 79 and 80 but I prefer to make the switches identical structurally and to produce the desired action, as hereinafter pointed out. By connecting the shunt coils to different points in the accelerating resistance, a higher voltage is applied to the one than to the other. As shown in the drawings, the higher voltage is applied to the coil 80 and, consequently, the magnet switch 56 has a greater tendency to move its armatures than has the switch 55. The air gaps existing at 82 and 83 are so adjusted that, as the motor speed increases and the current traversing the motor circuit is decreased, the armature 84 of switch 56 is first actuated and switch 85 is closed. As soon as this switch is closed, resistor section 54 is short circuited and the motor current is again increased so that the armature 86 is not actuated until the motor is still further accelerated. When the armature 86 finally moves, switch 87 is closed and both resistor sections 53 and 54 are short circuited. The voltage applied to the coil 79 of magnet switch 55 has consequently been increased and, upon the next reduction of motor current, armature 88 will be actuated and resistor section 52 be short circuited, armature 89 and resistor section 51 being finally short circuited by reason of an adjustment of the air gaps of the switch 55 corresponding to that of the air gaps 82 and 83 of switch 56.

The relay switch 70 forms no part of my present invention and is so arranged as to re-insert the accelerating resistance in case of a predetermined overload current traversing the motor circuit. If the motor current becomes very excessive, the overload release circuit breaker 77 will be actuated to positively interrupt the circuit.

Referring to Fig. 4 of the drawings, the system here shown corresponds to the system of Fig. 3 except that a reversing switch 90 is substituted for the switches 47 to 50, inclusive, and magnet switches 91 and 92, which correspond to the switch of Fig. 2, are substituted for the switches 55 and 56. Corresponding parts in the two systems are designated by the same reference characters.

The operation of the system of Fig. 4 is as follows: Assuming that master switch 57 is moved to position *a*, energy is supplied from line conductor 45, through the master switch 57, conductor 93, coil 94 of the reversing switch 90, conductor 95, switch 57 and conductor 96 to opposite line conductor 46. When coil 94 is energized, reversing switch arms 97 and 98 are moved in opposite directions away from each other, and the motor circuit is completed from conductor 45 through conductor 99, the field-magnet winding 75, conductor 100, switch contact 97^a, conductor 101, motor armature 67, conductor 102, switch contact 98^a, conductor 103, series coils 104 and 105, resistor sections 51 to 54, inclusive, and conductor 106 to the other line conductor 46. Since the current traverses the coils 104 and 105, the magnet switches 91 and 92 will be quite strongly energized when the reversing switch is first closed and the motor circuit is first established, then, as the motor speed increases, the motor current will be materially reduced until the armature 107 of the switch 92 is actuated and the switch 108 is closed in accordance with the principles of operation outlined in connection with the description of the device shown in Fig. 2.

As soon as switch 108 is closed, resistor section 54 is short circuited and the resulting increase in the motor current serves to still further delay the action of the armature 109 of the switch 92 and the armatures 110 and 111 of magnet switch 91, which will operate successively in the order named to short circuit the resistance sections 53, 52 and 51. The armatures are made to operate in the proper succession by adjusting the air gaps as explained in connection with the magnet illustrated in Fig. 2, but it may also be found desirable to provide the coils 104 and 105 with different numbers of turns.

Referring to Figs. 5 and 6 of the drawings the magnet switch here shown is similar to that shown in Fig. 2 of the drawings and corresponding parts are indicated by the same reference characters except that

there are four branches 27 and four independently movable core members or armatures 30, the end member 28 being cruciform, as shown in Fig. 6.

The air gaps existing between the members 30 and the ends of the member 28 are adjusted so that the four armatures operate in a predetermined sequence. Movable switch contact members are secured to the armatures 30 and are adapted to coöperate with stationary contact members as in Fig. 2. By means of the arrangement shown in Fig. 5, four independently operated accelerating switches of the usual type may be replaced by a single magnet switch of the type here shown and, since four accelerating steps are sufficient in a great many instances, it is evident that a very simple controller embodying only a single magnetic switch may be employed.

It is evident that magnet switches embodying my invention may be adapted for use with a variety of systems of control and that the structure of the switches themselves may be materially varied within the spirit and scope of my invention, since I believe that I am the first and original inventor of magnetic devices having the operating characteristics outlined above.

I claim as my invention:

1. An electromagnet comprising a stationary magnetizable member, a movable magnetizable member, and two coils for energizing said members with magnetism of the same polarity, said magnetism having a normal flux path that tends to produce relative movement between said members and a leakage flux path that tends to prevent relative movement between said members.

2. The combination with a movable element, of means for actuating said element and a magnet the leakage flux of which is adapted to prevent the actuation of said element.

3. The combination with a movable member, of a plurality of means for creating a magnetic field for controlling said member and means controlled by the leakage flux of said field for preventing the actuation of said member.

4. The combination with a movable member, of means for creating a plurality of magnetic fields for controlling said member and means controlled by the leakage flux of said fields for preventing the actuation of said member.

5. A magnet comprising two coils and a magnetizable member having two positions, the leakage flux due to one of said coils tending to maintain said member in one of said positions and the flux due to the other coil serving to maintain said member in said other position.

6. An electromagnetic switch having a series coil and a shunt coil, means whereby

- the leakage flux due to said series coil tends to maintain said switch open; and means whereby the flux due to said shunt coil serves to maintain said switch closed.
5. 7. A controlling device for electric circuits comprising a switch member normally biased to open position, a plurality of means for creating a magnetic field, and means whereby the leakage flux of said field holds the switch member in open position.
10. 8. An electromagnetic switch having two coils for creating two supplementing magnetic fields, one of said fields opposing the closing of said switch and the other of said fields serving to hold said switch in closed position.
15. 9. The combination with a movable member, of two coils for creating two supplementing magnetic circuits for controlling said member, the leakage flux of one of said circuits preventing the actuation of said member and said other circuit serving to hold said member in actuated position.
20. 10. An electric switch having two coils, means whereby the leakage flux produced by one of said coils tends to maintain said switch open and means whereby the leakage flux produced by the other of said coils tends to close said switch.
25. 11. The combination with a movable element, of a magnet for exerting opposing forces upon said element and a magnet the leakage flux of which is adapted to additionally act upon said element in the direction of one of said forces.
30. 12. The combination with an electric motor having an armature, and a source of current for said motor, of a switch for controlling said motor, a magnetizable member for controlling said switch, a coil connected to said source for controlling both ends of said member, and a coil in series with said armature for controlling one end only of said member.
35. 13. The combination with a movable member having two magnetizable portions, of a shunt coil for both of said portions and a series coil for one only of said portions.
40. 14. An electromagnetic switch provided with a coil having shunt characteristics and a coil having series characteristics for creating two magnetic fields adapted to act cumulatively to maintain said switch open in opposition to the force of the field of said coil having shunt characteristics.
45. 15. An electromagnetic switch comprising an armature, a lockout coil acting upon said armature to maintain said switch open and a closing coil acting oppositely upon said armature with forces adapted, respectively, to aid said lockout coil to maintain said switch open and to close said switch.
50. 16. The combination with a magnetizable frame having a recess, of an armature having a projection adapted to extend into said recess and means for energizing said frame to act oppositely upon said armature and said projection.
55. 17. The combination with a pair of relatively movable magnetizable members, of a series coil and a shunt coil for energizing said magnetizable members with magnetism of one polarity, said magnetism having a normal flux path that tends to produce relative movement between said members and a leakage flux path that tends to prevent relative movement between said members.
60. 18. The combination with a pair of coaxial, separately mounted coils, of an armature of U-shape one of the legs of which extends between said coils and the other leg of which is adapted to be attracted by one of said coils.
65. 19. In a system of motor control, the combination with a motor and an accelerating resistance, of a magnet switch for governing the resistance having a stationary magnetizable member, stationary switch contact members, movable magnetizable members, contact members secured thereto and a voltage coil tending to actuate the movable members and close the switches, and a current coil operating in the same direction electrically but opposing the action of the movable members when the motor current exceeds a predetermined amount.
70. 20. In a system of motor control, the combination with a motor having an armature and an accelerating resistor in circuit therewith, and a source of current for said motor, of a magnet switch for governing said resistor having a coil in series with said armature, means whereby the leakage flux of said series coil maintains said switch open when the current traversing said motor exceeds a predetermined value, and a coil connected to said source for maintaining said switch closed.
75. 21. The combination with a movable element, of means tending to maintain said element in a predetermined position and a magnet the leakage flux of which is adapted to prevent the actuation of said element to said predetermined position.
80. 22. The combination with a movable element, of an electromagnet for exerting opposing forces upon said element and an electromagnet for additionally acting upon said element in the direction of one of said forces.
85. 23. The combination with a movable switch member, of a series coil and a shunt coil for controlling said member, each adapted to create a magnetic flux, the magnetic flux of said shunt coil having a normal flux path distinct from the flux path of said series coil, and a leakage flux path that coincides in part with said flux path of said series coil, the flux traversing said normal flux path being adapted to effect the closing of said switch member, and the flux traversing
90. 95. 100. 105. 110. 115. 120. 125. 130.

- said flux path of said series coil being adapted to maintain said switch member open, whereby variations due to voltage or temperature of said shunt coil affecting the fluxes traversing both said normal flux path and the coinciding part of the flux path of said series coil do not affect the control of said member.
24. In a switch, the combination with a core member and a movable switch member, of a lockout coil and a closing coil, fluxes of the latter exerting opposing forces upon the movable switch member, and means so positioned as to effect the closing of said switch at a predetermined current flow in said lockout coil, irrespective of temperature and voltage changes in said closing coil.
25. An electromagnetic switch having a movable switch member, electromagnetic means for closing said member and for compensating for variations in the degree of energization of said electromagnetic means, and electromagnetic means for opposing the movement of said member.
26. An electromagnetic switch having a movable member, electromagnetic means comprising a shunt coil for actuating the same and for compensating for variations in the actuating force because of variations in the value of the current traversing said coil, and a series lockout electromagnet for opposing the movement of said member.
27. An electromagnetic switch having a movable switch member, an electromagnet comprising a series coil tending to retain said member in its open position, and electromagnetic means for closing said member and for compensating for variations in the energization of said electromagnetic means whereby said switch member is actuated to its closed position when the current traversing the series coil falls to a predetermined value, irrespective of temperature and voltage changes in said electromagnetic means.
28. An electromagnetic switch having a movable switch member, an electromagnet comprising a series coil tending to retain said member in its open position, and electromagnetic means comprising a shunt coil for closing said member and for compensating for variations in the energization of said electromagnetic means whereby said switch member is actuated to its closed position when the current traversing the series coil falls to a predetermined value, irrespective of temperature and voltage changes in said electromagnetic means.

In testimony whereof, I have hereunto subscribed my name this 17th day of May 1911.

HARRY A. LEWIS.
